United States Patent Office.

SUSAN C. CURRIE, OF NEW YORK, N. Y.

Letters Patent No. 90,997, dated June 8, 1869.

IMPROVEMENT IN POCKET-BOOKS.

The Schedule referred to in these Letters Patent and making part of the same.

To all whom it may concern:

Be it known that I, SUSAN C. CURRIE, of the city, county, and State of New York, have invented a new and useful Improvement in Fastening and Safety-Pin for Portemonnaies; and I do hereby declare that the following is a full, clear, and exact description thereof, which will enable others skilled in the art to make and use the same, reference being had to the accompanying drawing, forming part of this specification.

This invention relates to new and useful improvements in portemonnaies, pocket-books, and articles of a similar description, which are used for containing or carrying money, papers, or other valuables; and

It consists in providing an elastic adjustable fastening and a safety-pin for the portemonnaie, wallet, pocket-book, or other article, as will be hereinafter more fully described.

In the accompanying plate of drawings, a portemonnaie is shown with my fastening and safety-pin attached.

A is the portemonnaie, the same or similar to those ordinarily carried in the pocket.

B is the fastening, which consists of an elastic band, provided with metallic plates c, each plate having a hole for fastening on to a small knob, d.

The fastening-band B is secured to the flap E by an eyelet-fastening, f, through the plate g.

The knob or hook d is rigidly attached to the plate g.

The band B is sufficiently elastic to allow the portemonnaie to expand and contract, according to its bulk or contents, and the adjusting-plates c allow it to be tightly fastened, whether it is full or not, thus rendering it unnecessary to draw the fastening-band so tightly as to soon destroy it, as is usually done. The band is tipped by the adjusting-plate on its ends, as seen in the drawings. These plates are fastened to

the band by eyelets, which eyelets form the holes for fastening the knob d.

H represents the safety-pin, which is connected with the portemonnaie by a jointed finger, i, and plate j, as seen in the drawing, or in any other suitable manner.

k is the chain.

The pin-fastening is similar to an ordinary breast-pin.

This pin may be fastened to the dress or pocket of a gentleman or lady, so as to be a perfect protection while the portemonnaie is in the pocket. It enables a lady to attach it securely to any part of her dress when travelling in the cars or elsewhere, and at night the portemonnaie or pocket-book may be attached to any part of the night-clothes, or to the pillow, so as to be perfectly secure.

A portemonnaie, wallet, pocket-book, or any other similar article, constructed in this manner, may be kept in a proper condition by the adjustable fastening, and be perfectly secure from the depredations of thieves and pickpockets at all times.

Having thus described my invention,

I claim as new, and desire to secure by Letters Patent—

1. The adjustable elastic band-fastening and the safety-pin, whether used in combination or separately, when applied to a portemonnaie, wallet, pocket-book, or other article of a similar nature, substantially as and for the purpose described.

2. In combination with a portemonnaie, the safety-chain K, arranged substantially as and for the purpose set forth.

SUSAN C. CURRIE.
